(57) **CLAIM**

The ornamental design for a guitar stand as shown and described.

DESCRIPTION

FIG. 1 is a perspective view of a guitar stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the guitar stand where the guitar stand is in a folded state;

FIG. 10 is a perspective view of the guitar stand where the guitar stand is fully unfolded; and,

FIG. 11 is an enlarged view of portion 11 shown in FIG. 1. The dash-dash broken lines in the drawings depict portions of the guitar stand that form no part of the claimed design. The dot-dash broken lines represent the boundary of the enlarged portion and form no part of the claimed design.

1 Claim, 11 Drawing Sheets
